Inventor:
E. A. Stevens

UNITED STATES PATENT OFFICE.

EDWIN A. STEVENS, OF HOBOKEN, NEW JERSEY.

IMPROVEMENT IN SIGHTING GUNS.

Specification forming part of Letters Patent No. 37,365, dated January 6, 1863.

To all whom it may concern:

Be it known that I, EDWIN A. STEVENS, of Hoboken, in the county of Hudson and State of New Jersey, have invented certain new and useful Improvements in Sighting and Working Ordnance; and I do hereby declare the following to be a full and exact description of the same, reference being had to the accompanying drawings, making part of this specification, in which—

Figure 1 is a side elevation of a gun-boat, partly in section. Fig. 2 is a plan of the same.

Similar letters of reference indicate corresponding parts in both views.

My present improvements consist in arranging any or all the guns of a war-vessel so that they can be pointed to strike the same object, by means of graduated index-plates, by men standing below the deck above which the guns are placed, and so that they can be pointed toward any object desired by changing their position or the course of the vessel, as hereinafter explained.

My improvements further consist in the use of telescopes of peculiar construction, by means of which, either with or without graduated index-plates, cannon situated above the shot-proof deck may be accurately sighted by a gunner standing below the said deck. In order to bring the guns to bear, the course of the vessel may be changed by the helm when under headway, or, in case a double propelling-power (such as two screws) be used, by changing her position without making headway, or while making but little headway, by backing one screw and moving the other ahead. The men who train the guns, being under the gun-deck, would be protected either by the armor of the ship or by being under the water-line. The recoil of the guns would be taken up by india-rubber or other elastic material placed behind the trunnions or carriages, so that the guns which are attached to the carriages might be pointed from below the gun-deck. A pointer attached to the pintle or turn-table would point to the graduations on the index-plate by which the gun would be pointed, or the index-plate would be attached to the turn-table or pintle, or this apparatus might be arranged as circumstances might render most convenient. All the guns having been thus set by the index-plate to the angle ordered by the commander, the order would be given to

fire at the instant when the vessel had turned, so as to make them bear in the right direction, and all the guns could be thus fired at the same instant or successively at the same object by electricity or otherwise; or the guns may all be pointed permanently parallel to the keel, or in any direction, and aimed at any point by the man at the helm, as described. By means of two telescopes or other glasses going through the shot-proof deck, and having two prisms or mirrors, so as to throw the object down and then horizontally, and arranged with a graduated index-plate, the position of the enemy could be accurately ascertained from below the shot-proof deck. The angle of the enemy, as shown by the glass, with the line between these two glasses, and the length of said line being known, the distance of the enemy and the bearing of each gun in order to hit him are a matter of simple calculation, and may be tabulated beforehand; or these glasses may be under or over or at the side of the guns themselves, so that the guns may be pointed exactly, according to the index-plate on the glass, by a man below deck. The said glasses are so arranged that if shot away they may be easily replaced.

To enable others skilled in the art to fully understand and use my said invention, I will proceed to describe the accompanying drawings, which illustrate two different ways of carrying it into effect.

A represents the hull of the vessel, and B a shot-proof deck of any suitable construction.

C C are cannon mounted upon carriages D, which are adapted to be rotated in horizontal planes by means of pintles E E.

F F are telescopes of peculiar construction, formed with horizontal ends and a central portion, which passes vertically through the shot-proof deck B and is adapted to turn therein. By means of prisms or mirrors placed at the angles ff of the telescope, the rays are projected downward and then horizontally, so that any external object toward which the telescope is presented may be viewed by an observer below the deck.

G G are graduated disks secured beneath the deck concentrically with the telescopes F and gun-pintles E, respectively.

H H are pointers projecting from the said telescopes and pintles over or under the faces of the graduated disks, in order to indicate ac-

curately the directions in which the telescopes and guns point.

Similar telescopes may be applied directly to the gun-carriage, as shown at F' in Fig. 1, and by this means the guns may be sighted separately from below deck without the use of graduated index-plates.

Having described in separate applications various methods of applying the recoil and counter-recoil springs and devices for training, elevating, cleaning, and loading the guns, a specific description of the same is not required here. These and other necessary parts not herein described may be constructed and arranged in any suitable manner.

I I (shown by dotted lines in Fig. 2) are two screw-propellers, by means of which the vessel may be propelled and turned in any manner desired.

The following is what I claim as new in the above-described invention and desire to secure by Letters Patent:

1. The use of a graduated index-plate situated below the gun-deck for pointing the guns of war-vessels, substantially as described.

2. The use of graduated index-plates for turning the guns of war-vessels, in combination with two screw-propellers for turning war-vessels, for the purposes specified.

3. A telescope, F f, constructed substantially as described, in combination with a revolving gun-carriage, for the objects specified.

4. The use of two telescopes, constructed substantially as described, for observing from within or below a protected structure the distance and position of an object, for the purpose specified.

E. A. STEVENS.
